UNITED STATES PATENT OFFICE

140,592

DESIGN FOR A TRUCK CRANE

Harold A. Wagner and Gustave H. Wagner,
Portland, Oreg.

Application August 8, 1944, Serial No. 114,783

Term of patent 14 years

(Cl. D14—3)

To all whom it may concern:

Be it known that we, Harold A. Wagner and Gustave H. Wagner, citizens of the United States, residing at Portland, in the county of Multnomah, State of Oregon, have invented a new, original, and ornamental Design for a Truck Crane, of which the following is a specification, reference being had to the accompanying drawings, forming a part thereof.

In the drawings, Fig. 1 is a side elevational view of the truck crane showing our new design as it appears when in the operative position, a portion of the boom and hoist ropes being broken away for convenience of illustration; Fig. 2 is a side elevational view of the truck crane in the inoperative position for transportation and with the clam-shell bucket removed; Fig. 3 is a top

plan view of the truck crane illustrated in Fig. 2; Fig. 4 is a side elevational view of the truck crane illustrating the side opposite to that shown in Fig. 2; Fig. 5 is a front elevational view of the truck crane as shown in Fig. 4; Fig. 6 is a rear elevational view thereof as shown in Fig. 4; and Fig. 7 is a perspective view from the front of the truck crane in the operative position and with the crane cab facing forwardly, the upper end portions of the boom, cables and clam-shell bucket being deleted for convenience of illustration.

We claim:

The ornamental design for a truck crane, substantially as shown.

HAROLD A. WAGNER.
GUSTAVE H. WAGNER.
